[57] CLAIM

The ornamental design for an armored seal for toggle type switches, as shown and described.

DESCRIPTION

FIG. 1 is a perspective view from the front above of the armored seal for toggle type switches showing my new design;

FIG. 2 is a top plan view thereof;

FIG. 3 is a front elevational view thereof, the rear elevational view being the same; and

FIG. 4 is a bottom plan view thereof.

FIG-1

FIG-2

FIG-3

FIG-4
